STOVE DOOR FRAME AND DOOR

Christopher L. Hardwick, Cleveland, Tenn.

Application March 28, 1946, Serial No. 657,667

2 Claims. (Cl. 126—194)

1

This invention relates to improved means for hingedly mounting the doors of stoves and the like.

Heretofore it has been the practice for stove manufacturers to assemble stove doors and frames to the stove body at the same time. It was, therefore, impossible to assure of the doors being level and straight and the necessary adjustments thereto often resulted in the enamel parts of the stove and doors being damaged or marred.

The principal object of the present invention is to equip stove doors and the like with adjustable hinge pin brackets to permit of the doors being made up as a subassembly independently of the stove itself and thereafter mounted on the stove by the manufacturer which tends to reduce breakage and damage to the stove body and doors to a minimum.

Another object is to provide a stove door with adjustable hinge pin brackets which permits of the door being assembled by use of a jig thereby assuring of the door being level and straight and permitting the door to be assembled independently of the stove.

Another object is to provide slidably mounted hinge pin brackets on stove doors which permit of easy assembly and disassembly and adjustment thereof to assure of a proper and uniform fit.

A further object is to provide hinge pin brackets for stove doors which may readily be adjusted to retain the hinge pins in the desired engagement with the stove body.

These and further objects and advantages will be apparent as the specification is considered in connection with the accompanying drawings wherein:

Figure 1 is a rear elevation of a door and frame embodying my invention;

Figure 2 is a vertical transverse sectional view on the line 2—2 of Figure 1 showing the door in closed position;

Figure 3 is an enlarged vertical fragmentary transverse sectional view of a portion of the door and frame;

Figure 4 is a fragmentary longitudinal section on the line 4—4 of Figure 3, showing the hinge pin bracket and pin and the adjustable mounting on the door frame;

Figure 5 is a vertical fragmentary sectional view on the line 5—5 of Figure 4; and

Figure 6 is a perspective view of one of the hinge pin brackets.

Referring more particularly to the drawings wherein like reference characters designate simi-

2

lar parts throughout the several views, the numeral 1 refers generally to a rectangular metal door frame having a door and drawer openings 2 and 3 therein, as illustrated in Figure 1. The outer marginal edge of the frame 1 is bent rearwardly, as at 4, to permit of the frame being seated within an opening in the front of the stove frame, not shown, and secured thereto in any suitable manner by fastening devices such as screws or the like, also not shown. It will be understood that a drawer, not shown, is adapted to be slidably positioned within the frame opening 3 and to extend into the stove body in a conventional manner.

15 A door 5, hingedly mounted in the frame door opening 2 in a manner hereinafter described, comprises a front sheet metal enameled plate 6 and a rear sheet metal plate 7. The edge portions of the front plate are bent rearwardly to 20 form a continuous peripheral flange 8 which is adapted to overlie and fit closely with a forwardly extending peripheral flange 9 formed on the rear plate. The flange 8 extending along the bottom of the front plate is provided with an upturned flange 10 which engages with the lower edge of 25 the rear plate 7 and serves to hold the plates together. The plates are clamped together by spaced screws or the like 11. Insulating material 12 is preferably interposed in the space between the front and rear plates according to well established practice.

The door 5 is hingedly connected to the door frame by my improved concealed hinge construction comprised of two substantially L-shaped metal hinge brackets 13. As the brackets 13 are identical only one will be described. Thus each bracket 13 is formed with a substantially horizontal flat base portion 14 and an upwardly extending side portion 15, and is slidably connected to the back plate 7 in a manner hereinafter described. The inner end of a metal hinge pin 16, is snugly and immovably fitted into one of two apertures 17—17' extending through the upper end of the side portion 15 of the bracket 13. The pin may be press fitted or otherwise secured within the aperture, as by welding or the like. The base portion 14 is also provided with two apertures 18—18' extending therethrough to permit of the bracket being attached to the door 5, when the brackets are being assembled in place between the front and rear plates thereof. One of the apertures 18—18' in each of the brackets 13 will be aligned with a short horizontal slot 19 extending through the 55 rear plate 7 adjacent the bottom marginal edge

thereof, as best illustrated in Figures 1 and 4, to permit of a screw or the like 20 being inserted through the aligned slots and apertures for clamping the hinge brackets in desired adjusted position on the door. Hinge pins 16 are aligned with and project laterally through apertures 21 in the side peripheral flanges 9 of the rear plate 7, and extend through apertures 23 in the lower end of an extension 24 depending from each of two brackets 22 and projecting forwardly through a vertical slot 26 in each of the side portions 25 of the stove door frame 1. The brackets 22 are secured to the frame 1 by any suitable means such as screws or the like 27 so that the hinge pins 16 serve to hingedly mount the door on the frame.

In order to facilitate the opening and closing of the door, two downwardly depending curved webs 28 having upturned lower ends 29 are formed on or suitably attached to the side peripheral flanges 9 of the rear plate 7. Springs 31, anchored at their lower ends in openings 32 in the lower end portion of frame 1, are attached at their upper ends to the bent lower ends of metal fastening clips 33, the bent upper ends of which are in turn hooked over the lower ends 29 of the webs 28. It will, therefore, be apparent that the springs serve to yieldingly retain the door in closed position. The springs 31 and clips 33 may readily be connected to and/or disconnected from the webs 28 when assembling and disassembling the door. The lower ends 29 of the webs are provided with shoulders 30 adapted to engage with the rear face of the door frame 1 and limit the opening movement of the door 5.

It is important that each of the side and base portions of the brackets 13 be provided with two openings 17-17' and 18-18' as this permits of the brackets being interchangeable. That is, when a bracket 13 is mounted, as previously described, on the left side of the door, viewing Figure 1, the hinge pin 16 will be positioned in the opening 17', to permit of the pin being aligned with and extended through the opening 21 in the flange 9 of rear door plate 7. The attaching screw 20 will extend through the opening 18' in the base portion of the bracket. On the other hand, when a bracket 13 is mounted on the right side of the door, viewing Figure 1, the bracket will be oppositely arranged from the left hand bracket, so that the hinge pin 16 must necessarily be positioned in the opening 17 to align the pin with the opening 21 in flange 9 and permit the same to extend therethrough, and the attaching screw 20 will extend through the opening 18 in the base portion of the bracket. It will, therefore, be understood that the provision of four openings 17-17' and 18-18' in the brackets permits of the same type bracket being mounted on both sides of the door. This reduces manufacturing costs and facilitates assembly and disassembly of the hinge pin brackets, in an obvious manner.

As the screws 20, used in connecting the hinge pin brackets 13 to the rear door-plate 7, extend through the longitudinal slots 19 in the plate 7, it will be understood that the brackets 13 may be readily moved for adjusting the hinge pins 16, by loosening the screws. This is particularly desirable because it permits of the stove door being assembled as a subassembly unit independently

of the stove. In such cases, the door will be completely assembled by the manufacturer with the hinge pin brackets mounted thereon, which enables the complete door unit to be readily mounted on the stove as a unit prior to shipment. Assembly of the door on the stove is readily effected by adjusting the hinge pin brackets, so that the pins interconnect with the stove frame brackets 22, and thereafter tightening the hinge pin bracket screws 20 and finally securing the clips 33 and springs 31 in place.

It is to be understood that various changes may be made in my invention without departing from the scope and spirit of the appended claims.

Having thus described my invention what I claim is:

1. A stove door frame, a door mounted therein and having front and back plates, means for securing said plates together, a hinge bracket member mounted on said back plate, said member having a substantially flat base portion and a substantially flat side portion formed on one end thereof and extending at right angles to said base portion, said side portion having spaced apertures therein, a hinge pin mounted in one of said apertures, bracket members secured to the frame and having apertures therein for receiving said hinge pin said base portion having spaced apertures therein, said back plate having an elongated opening therein, and fastening means extending through said opening and one of the apertures in said base portion for adjustably connecting said bracket member to said back plate.

2. A stove door frame, a door mounted therein and having front and back plates, means for securing said plates together, a substantially L-shaped hinge bracket member interposed between said plates, said member having a substantially flat base portion and a substantially flat side portion integrally formed on one end thereof and extending at right angles to said base portion, of said bracket member having spaced apertures therein, a hinge pin fixedly mounted in one of said apertures, bracket members secured to the frame and having apertures therein for receiving said hinge pin, said back plate having an elongated opening therein, and fastening means extending through said elongated opening and one of the apertures in the base portion of said hinge bracket member for adjustably connecting said hinge bracket to said back plate.

CHRISTOPHER L. HARDWICK.
